W. J. TANNER.

ELECTRICAL APPARATUS FOR SEPARATING GOLD FROM ORES.

No. 328,532.

Patented Oct. 20, 1885.

The diagram illustrates a two-stage magnetic circuit, labeled Fig. 5, showing the magnetic flux distribution and field components. The circuit consists of two vertical legs, A and B, and a horizontal core section.

- Leg A:** The left vertical leg has a rectangular cross-section. It features a vertical air gap of width q and a core of thickness σ . The magnetic flux density in the core is labeled σ , and the total flux in the leg is Φ_A . The air gap has a flux density of σ_g .
- Leg B:** The right vertical leg has a rectangular cross-section. It features a vertical air gap of width q and a core of thickness σ . The magnetic flux density in the core is labeled σ , and the total flux in the leg is Φ_B . The air gap has a flux density of σ_g .
- Core:** A horizontal core section connects the two legs. It has a rectangular cross-section with a thickness σ . The magnetic flux density in the core is labeled σ , and the total flux in the core section is Φ_C .
- Flux Components:** The total flux Φ is the sum of the fluxes in the two legs and the core: $\Phi = \Phi_A + \Phi_B + \Phi_C$.
- Field Components:** The diagram shows the components of the magnetic field $\mathbf{H}$ and the magnetic field intensity $\mathbf{B}$ at various points. At point P in Leg A, the field components are H_x and H_z . At point Q in Leg B, the field components are H_x and H_z . At point R in the core, the field components are H_x and H_z .
- Flux Density Components:** The diagram also shows the components of the magnetic flux density σ at various points. At point P in Leg A, the flux density components are σ_x and σ_z . At point Q in Leg B, the flux density components are σ_x and σ_z . At point R in the core, the flux density components are σ_x and σ_z .

UNITED STATES PATENT OFFICE.

WILLIAM J. TANNER, OF LONDON, COUNTY OF MIDDLESEX, ENGLAND.

ELECTRICAL APPARATUS FOR SEPARATING GOLD FROM ORES.

SPECIFICATION forming part of Letters Patent No. 328,532, dated October 20, 1885.

Application filed September 24, 1884. Serial No. 143,833. (No model.)

To all whom it may concern:

Be it known that I, WILLIAM JOHN TANNER, a subject of the Queen of Great Britain and Ireland, and a resident of London, county 5 of Middlesex, England, have invented certain Improvements in Electrical Apparatus for Washing and Separating Gold and Silver from their Ores, of which the following is a specification.

It is well known that when amalgam plates are used for collecting gold and silver from their ores the surfaces of these plates are liable to become tarnished or sickened by certain substances contained in the ores or in the current of water which is employed to carry the ore over the plates, and that in this condition they are unfitted for amalgamating the particles of gold and silver. To prevent this and to keep the surfaces of the amalgam plates 15 always bright and in a better condition for catching and amalgamating the particles of gold and silver I employ electricity in the following manner:

The ore is carried over the plates by a stream 25 of water in the usual manner, and I arrange, touching the water, but not touching the plates, one or more bars, plates, or points of carbon, after the manner shown in the accompanying drawings. The bars, plates, &c., of carbon 30 may be secured to a frame and supported at the proper height above the amalgam plate or plates and in such manner that the carbon bars, &c., may be in the direction of the current of ore and water, or in a direction trans- 35 versely thereto. The carbon bars, &c., are electrically connected with the positive pole of a battery or other source of electricity, and form, therefore, the anode, while the amalgam plates are connected with the negative pole and 40 form the cathode. The current of electricity passes from the carbon through the water to the amalgam plates, and keeps these free from tarnishing or sickening. In cases where it is 45 desired to pass large quantities of ore with the water, the fixed bars, rods, &c., of carbon are liable to cause obstruction. To avoid this, and also with the object of economizing the quantity of electricity employed, I use one or 50 more bars, plates, rods, or the like of carbon over each amalgam plate or plates, and I cause these bars, plates, &c., to travel backward and forward over the surface of the

amalgam plate or plates by any suitable mechanical arrangement, such as that hereinafter described. The carbon bars, &c., touch the 55 water during the whole or a portion of their stroke, but in no case come in contact with the plate or plates. The electrical connections are made in the same manner as before described—viz., the carbon the anode, and 60 the amalgam plates the cathode. To avoid still further any obstruction to the ore and water, I sometimes employ in addition to this a simple mechanical arrangement, such as is shown in the drawings, whereby the carbon is 65 raised out of the ore and water during the return-stroke—that is, when traveling in a direction opposite to that of the current of ore and water. I also sometimes cause the carbons to traverse above the amalgam plate or 70 plates in a line at right angles to the direction of the flow of ore and water, as the movement of the carbons in this direction causes less obstruction to the current of ore and water.

Again, in cases where I am treating an ore 75 which has only a moderate sickening effect on the amalgam plates I move the carbon anode or bars by hand. At each end of the bar of carbon is mounted a small wheel of ebonite, glass, or other suitable non-conducting material, and 80 these wheels are so arranged as to prevent the carbon touching the amalgam plate or plates, but to allow of its touching the water, as before described. A handle of convenient length is attached to the carbon bar, and the electrical connections are the same as before described. A flexible metallic conductor conveys the current to the carbon, and the carbon is traversed over the plates as frequently 85 as is found necessary to keep them in good 90 condition.

Instead of mounting the carbon on insulating-wheels, it may be in the form of a cylinder, having two or more rings around it made of india-rubber or other non-conducting material. The carbon cylinder has a metallic pin at each end, and the whole is mounted in a frame provided with a suitable handle. The electrical connections are made as before described, the current passing through the metallic pins to the carbon.

In cases where there is much float-gold I sometimes employ a cylinder of amalgamated copper, rolling above but not touching a sur-

face of carbon plates over which the ore and water are passing, the cylinder being in this case the cathode, and the carbon plates the anode, and, as before stated, the carbon and copper do not come in contact with each other, but the water conveys the current from the one to the other. Strips of insulating material separate the cylinder of amalgamated copper from the carbon plates over which it is caused to travel.

I now proceed to describe fully the construction of apparatus as shown in the drawings, and employed for carrying my invention into effect.

15 Similar letters indicate like or corresponding parts in all the figures.

Figure 1 is a plan, and Fig. 1^x a longitudinal section, of a portion of an apparatus wherein the carbon rods, &c., are arranged in the direction of the current of ore and water. The carbons A are fastened to the cross-bars B, which support them at the proper height above the surface of the amalgam plate C by resting on the sides D of the table E, on which 20 the amalgam plates are laid or fastened. The carbons A are connected with the positive pole of the source of electricity by a strip or strips of metal or other conducting material, F, placed between the carbons A and one or 25 both of the supporting-bars B. The amalgam plates are connected, by any suitable means, with the negative pole of the same 30 source of electricity.

Fig. 2 is a plan, and Fig. 2^x a longitudinal section, of an arrangement in which the carbon rods, &c., are placed in a direction across the current of ore and water. A are the carbon rods, which are fastened to the bars B, which in their turn are fastened to the bars 35 B^x, resting on the sides D of the table E, so as to keep the carbons at the proper height above the surface of the amalgam plate C. The carbons are connected with the positive pole of the source of electricity by means of the strip or strips of metal or other conducting material, F, (shown in dotted lines,) placed between the carbons and one or both of the bars B. The amalgam plate C is connected by any 40 suitable means with the negative pole of the same source of electricity.

Fig. 3 is a plan, and Fig 3^x a longitudinal section, showing a method of moving the carbon plates, bars, &c., to and fro over and above the surface of the amalgam plate or plates. The carbon plates, bars, &c., A, are fastened to the cross-bars B, resting on the sides D of the table E, on which are laid or fastened the amalgam plates C. The ends of the bars B are joined by the longitudinal bars 45 B^x by being screwed or similarly fastened to them. These bars, with the cross-bars B and the carbons A, are moved to and fro by means of the connecting-rods G and the cranks H. The crank-shaft J is revolved by the pulley K, or any other suitable means. The carbons are connected in any suitable manner with the positive pole of the source of electricity,

and the amalgam plates with the negative pole of the same source.

Fig. 4 shows a side view, and Fig. 4' a cross-section on the line x x of Fig. 4, of a table fitted with an arrangement for raising the carbons out of the ore and water when making their return-stroke. The ends of the cross-bars B, which carry the carbons A, project 70 over the sides D D' of the table E and rest on the top of the longitudinal bar B^x, running along each side of the table and supported on but not fixed to wedge-shaped blocks L. These wedge-shaped blocks are connected with 75 one another by bars M, and can be slid up and down on the inclined planes N, fixed on the sides D of the table E. As in the previously-described apparatus, the bars B^x with the cross-bars B and the carbons A receive a to-and-fro motion by means of the connecting-rod G and the crank H, driven by the pulley 80 K, or any other suitable means. The blocks L are driven by the shorter cranks H^x on the opposite side of the crank-shaft to H, the crank H being connected with the bar M by means of the connecting-rod G^x. The arrangement of the two cranks is shown in plan, Fig. 4².

The drawing Fig. 4 shows the arrangement of cranks, sliding blocks, &c., on one 95 side of the table only, but there are like corresponding parts on the other side. When the bars B^x have been pushed as far from the crank-shaft as the crank H will allow, the wedge-shaped blocks L will have been slid up 100 the inclined planes N N by the shorter crank H^x and the connecting-rod G^x. They will therefore raise the side bars, B^x, together with the cross-bars B and carbons, and on the crank H having drawn the bars B^x as near 105 the crank-shaft as possible, the smaller crank will have pushed the wedge-shaped blocks L down the inclines N, and so lowered the carbons onto the surface of the ore and water passing over the surfaces of the amalgam plates. 110 The electrical connections of the carbons and amalgam plates to the respective poles of the source of electricity are made as in the previously-described arrangement.

Fig. 5 is a plan of an arrangement for causing the carbon bars, plates, &c., A, to traverse above the surface of the amalgam plate or plates in a direction at right angles to the direction of the current of ore and water. The carbons are fastened to the H-shaped frame 120 O, sliding on the top of the cross-bars, B, extending across the width of the table. The frame O is kept at right angles to the bars B by distance-pieces O (seen in dotted lines) fastened underneath it. The frame O, with 125 the carbons attached to it, is caused to traverse from side to side of the table by means of the bell-crank lever P P^x, slotted or forked at both ends and capable of turning on the pin p, which works in a socket fastened to one of the bars B. A pin, Q, projects from the center bar of the sliding-frame O and stands up in the slot q at the end of the arm P of the said bell-crank lever. All that is now neces-

sary is to move the arm P^x of the lever to and fro in the direction of the current of ore and water, when the end P , having the slot q , will, by means of the pin Q , cause the frame O , 5 with the carbons A , to traverse the current of ore and water at right angles to its direction. The required movement of P^x is effected in the following manner: Two guides, $R R$, are fixed on the side of the table, and in these 10 guides is a sliding bar, S , having at its side a pin, Q^x , to which one end of a connecting-rod, G , is attached, the other end of this rod being fastened to the crank H , revolved by pulley K or other suitable means. The 15 sliding bar S has another pin, Q^x , on its upper side, and at right angles to pin Q^x the pin Q^x stands up in the slot q^x at the end of arm P^x and communicates the to-and-fro motion of the bar S to the arm P^x of the lever 20 $P P^x$. The electrical connections with the respective poles of the source of electricity are made as in the previously described apparatus.

Fig. 6 is a plan, and Fig. 6 x a section, of an 25 apparatus to be passed over the surface of the amalgam plate or plates by hand, whenever the condition of the plate or plates is such as to render the application of electricity necessary for the purpose above set forth. The 30 carbon bar or rod A has fastened to its ends the wheels T , made of non-conducting material, and of such a diameter that when they are rolled on the surface of the amalgam plate C the carbon bar or rod A will be at the 35 proper height above the plate. To the carbon is attached the socket U , made of metal or other good conducting material. Into this socket is fitted the handle V , made of non-conducting material. A metallic conductor, 40 F , connected with the socket U , passes through the handle V , and by means of the flexible conductor F^x puts the carbon A in electrical connection with the positive pole of a source of electricity. The amalgam plate is suitably 45 connected with the negative pole of the same source.

Fig. 7 is a sectional plan of a modification of the hand apparatus above described. In this case the carbon A is in the form of a 50 roller, around which are placed the rings T^x , made of india-rubber or other non-conducting material, and by which the carbon is prevented from coming into contact with the amalgam

plate or plates over which it is being traversed. Metallic pins t are fixed in the ends 55 of the carbon A and turn in the ends t^x of the metal frame W , in the center of which frame is a socket, U , into which is fitted the handle V , made of non-conducting material. The electrical conductor F is fixed to this 60 socket and passed through the handle to the flexible conductor F^x , connected with the positive pole of a source of electricity, as in the previously-described apparatus.

Having now described the nature of my invention, what I claim, and desire to secure by Letters Patent, is—

1. The combination, with an amalgam plate over which the materials pass, of one or more bars or anodes of carbon, arranged above or 70 near and out of contact with the plate, said plate and bars being electrically connected and in electrical contact with the water and ore, substantially as described.

2. The combination, with an amalgam plate 75 over which the materials pass, of one or more bars or anodes of carbon, arranged and electrically connected, substantially as described and shown, and means for reciprocating said bars, for the purpose set forth. 80

3. The combination, with an amalgam plate over which the materials pass, of a reciprocating bar or anode of carbon, arranged and electrically connected, substantially as described, and means whereby said bar is raised 85 out of contact with the water during such time as the anode is moving in a direction opposite to the current of ore and water.

4. The combination, with an amalgam plate over which the materials pass, of a sliding 90 frame carrying a series of carbon bars or anodes, a crank connected to the frame, inclined planes or wings, wedge-shaped block between the inclined planes and the frame, and connected to a crank, the arrangement 95 being substantially as described.

In testimony that I claim the foregoing I have hereunto set my hand this 5th day of August, 1884.

W. J. TANNER.
